Attorney

UNITED STATES PATENT OFFICE.

JOHN M. SUNDEAN, OF HINCKLEY, MINNESOTA.

SEAM.

Application filed July 6, 1922. Serial No. 573,144.

To all whom it may concern:

Be it known that I, JOHN M. SUNDEAN, a citizen of the United States, residing at Hinckley, in the county of Pine and State 5 of Minnesota, have invented a new and useful Seam, of which the following is a specification.

This invention relates to seams and more particularly to seams for leather goods such 10 as shoes, mittens, baggage carriers and the like.

The object of the invention is to provide a flat seam of this character which is strong and durable and will not rip and by means 15 of which two pieces of leather may be stitched together and the stitches concealed without using any cover strip to effect such concealment.

Another object is to provide a seam for 20 connecting two pieces of leather in which one piece is slit on its inner face to provide an attaching lip which is secured to the other piece by a row of stitching passing through the lip at the base thereof, and 25 through the edge of the other piece so that when the parts are in operative position, a flat seam will be formed with the stitching invisible from both the inner and outer 30 faces of the device formed by the connected pieces.

With the foregoing and other objects in view which will appear as the description proceeds, the invention resides in the combination and arrangement of parts and in the 35 details of construction hereinafter described and claimed, it being understood that changes in the precise embodiment of the invention herein disclosed may be made within the scope of what is claimed without departing from the spirit of the invention.

In the accompanying drawings:—

Fig. 1 is a transverse section showing one form of the invention.

Fig. 2 is a detail transverse section showing the seam with the parts connected thereby in the position which they assume before being arranged flat in their normal position.

Fig. 3 is a detail transverse section showing still another form of the invention, and 50

Fig. 4 is a detail sectional view with the lips illustrated in Fig. 3 shown open ready for stitching.

In the form shown in Figs. 1 and 2, the leather pieces 1^a and 5^a are connected at a point spaced inwardly from the edge of the piece 5^a which piece is slit longitudinally on its inner face to form an attaching lip 8. This lip 8 tapers toward its free edge and the edge of the piece 1^a is secured to the lip 8 by a row of stitching 9 passing through said edge and through the base of the lip so that the stitching will not appear on the outer face of the member 5^a. After this edge of the member 1^a has been stitched in the manner above described, the piece 1^a is folded over into the position shown in Fig. 1 and the lining strip 4 secured over the seam so formed by a row of stitching passing through one edge thereof and through the 60 member 1^a at a point spaced laterally from the connection with the lip 8 and through the edge of the member 5^a. The strip 4 is also secured to the member 5^a on the other side of its seamed connection with member 1^a by a row of stitching 12 which also operates as a finish as well as to secure the strip 4 in position.

By stitching the edge 10 of member 1^a to the lip 8 at the base thereof, the stitching 70 will be invisible from the outer face of the connected parts and when the member 1^a is folded over in the position shown in Fig. 1 it will also be seamed on the inside.

In the form shown in Figs. 3 and 4, the 85 members 1^b and 5^b are connected similarly to those shown in Figs. 1 and 2 with the addition of a second seam formed by an attaching lip 13 arranged adjacent the member 1^b by a row of stitching 14 passing through said member and through the base of the lip.

From the above description it will be obvious that a seam constructed as herein shown and described in addition to having 90 the connecting stitches concealed to prevent

wear by rubbing on the stitching also is greatly strengthened and ripping thereof will be prevented.

I claim:—

- 5 The combination of two pieces of leather, one of which is split longitudinally on its inner face at a point spaced from its edge to provide an attaching lip, a row of stitches passing through the edge of the other piece
- 10 and said lip at the base thereof, the projecting edge portion of the lip-carrying piece

being turned down flat over the seam so formed and secured, whereby the stitches are rendered invisible from both faces of the so connected pieces.

15

In testimony that I claim the foregoing as my own, I have hereto affixed my signature in the presence of two witnesses.

JOHN M. SUNDEAN.
